HYDROLYSIS OF SCLEROPROTEINS WITH
ALCOHOLIC HYDROXIDE SOLUTION
Ervin J. Hawrylewicz and Irene D. Bludzus, Chicago,
Ill., assignors, by mesne assignments, to Reliable Pack-
ing Company, Chicago, Ill.
Filed June 20, 1963, Ser. No. 293,223
5 Claims. (Cl. 260—123.7)

This invention relates to proteins, and more in particular to the treatment of keratin.

Various methods are already known for the treatment of keratin, the keratin compound, such as contained in wool, horns, hoofs, feathers, hair and the like. All of these methods depend on hydrolysis, some with acids and some without acids.

The present invention belongs to the latter group and relates to the alkaline hydrolysis of hair. Certain materials are much easier to hydrolyze than others. For example, hoofs and horns have been treated with acid materials to obtain a hydrolytic product, using such materials as acid or acid chloride, all operating in strictly an acid medium. Certain other products, such as feathers, have been hydrolyzed by the use of steam under elevated temperature and pressure to produce a hydrolyzed product that has been used as a feed supplement.

Skins and certain tannery refuse have been treated in an alkaline medium to produce hydrolyzed products. This is usually accomplished by adding magnesia and basic magnesia carbonate to produce a solution having an alkalinity not greater than a pH of 9.5.

None of these processes are capable of hydrolyzing certain types of hair, such as hog hair.

It has also been proposed by Ward in his Patent No. 2,474,339 to hydrolyze certain material such as chicken feathers, using ethanol, water and mercaptoethanol at 80° C. This patent also refers to a treatment of hog hair where the hair is treated with ethyl alcohol, water and sodium hydroxide at a pH of 8.5, heated for a period of 4 hours at 130° C. in a sealed vessel.

Binkley, in his Patent No. 2,542,984 discloses a process for the hydrolysis of keratin materials, which comprises an alcohol, water and an acid which is heated at a temperature, preferably 110° C. to 150° C., under pressure. The pH of this solution is approximately 2.5 to 4.

The present application deals with a group of materials known as scleroproteins, which include both col-

2

by the synthetic fibers and is now a waste product on the market. Many attempts have been made to hydrolyze hog hair, so as to use it as a feed supplement, but all of these attempts have proven failures, because of the great difficulty in hydrolyzing the particular protein contained within this material, so as to render it suitable as a feed supplement.

It is an object of the present invention to provide a process that will produce a food protein.

It is also an object of this invention to produce from hog hair a hydrolyzed protein that is valuable as a feed supplement.

It is a still further object of this invention to provide a process that will hydrolyze scleroproteins, particularly keratin proteins, such as wool or hog hair to produce amino acids that are digestible and useful as a feed supplement.

It is a still further object of this invention to provide a process for hydrolyzing hair at room temperature, without pressure, in a short length of time and to maintain the maximum amount of cystine in the resulting product.

It is a still further object of this invention to avoid the use of mercapto compounds to solubilize keratin proteins.

These and other objects will be apparent to one skilled in the art from the various examples given below, but this invention is not limited by these examples, but is only limited by the claims appended hereto.

FIGURE 1 is a graph showing the rate of solubilization of hog hair.

FIGURE 2 is a chromatographic amino acid analysis of treated hog hair.

FIGURE 3 is a graphic representation of the effect of reaction time on the amino acid composition of treated hog hair.

FIGURE 4 is a graphic representation of the growth rate of rats maintained on soyabean meal and modified hog hair protein.

It has been found that hog hair will hydrolyze at room temperatures without pressure in 30 minutes or less when it is suspended, preferably with agitation, in an alcohol, preferably isopropyl alcohol, and sodium hydroxide if the pH is at least 11.5.

A pH of 10 does not give satisfactory results even under increased pressure. A pH of 11.5 or greater does give satisfactory results.

lagen and keratin type proteins. This group is noted for their extreme resistance to chemical agents, and includes skin, intestines and hair. Hog hair and wool are keratin type proteins, and particularly hog hair is noted for its extreme resistance to chemical attack. All of these materials are not attacked by trypsin and are therefore of no food value.

Hog hair has been a by-product of the packing industry for many years and has found various uses up to the present time. It has been replaced in most of these uses

65 Prior to treatment, the hog hair was washed and the lipid material removed. It will be noted from the tables (1 and 3) that the pH at which solubilization occurs appears to be critical.

Various alkaline materials have been tried, sodium hydroxide and potassium hydroxide have given satisfactory results. Ammonium hydroxide does not produce satisfactory results.

70 Ammonium hydroxide (NH₄OH) solutions were examined, for their effect on hog hair. Various conditions

were employed, as summarized in Table 2. However, under none of these conditions was any visible alteration in the hog hair noted.

1:40.....	0.8	24	b RT	12.0	0	-----

^a +, complete solubilization; -, no solubilization.
^b Room temperature.

Ammonium hydroxide within the critical pH of 12 to 14 failed to give any satisfactory results. Reducing agents such as sodium sulfite at pH of 12.6 and a temperature of 34° C. and a digestion period of 17½ hours, resulted in a 76% solubilization of hog hair. The addition of 5 mole of urea to this mixture resulted in little additional solubilization.

It will be noted from Table 3 that regardless of the concentration of sodium hydroxide the pH of the reaction solution is the most critical factor. Apparently the destruction of the peptide linkages takes place between a pH of 11 and 12 with no solubilization occurring below a pH of 11.

^a Aqueous sodium hydroxide.

Washed, lipid-extracted hair was suspended in 0.5 M thioglycolic acid solution in a ratio of 1:40. Urea was added to the suspension to a concentration of 10 M and the entire solution adjusted to pH 12.6. The entire mass was allowed to react for 17½ hours at 45° C. This resulted in 89.2% solubilization. The conditions of digestion were identical to those employed for the reaction between Na_2SO_3 and hair, in which case only 76.4% of the hair was hydrolyzed. It appears that thioglycolic acid is a more efficient reducing and hydrolyzing agent. However, the extreme reaction conditions, and the disagreeable character of this compound prevent it from being considered commercially.

The above experimental conditions were repeated with mercaptoethanol replacing thioglycolic acid. Under these conditions only 24.8% of the hog hair was solubilized in the prescribed time period of 17½ hours.

It has been found that hog hair will hydrolyze with sodium hydroxide. This action was greatly accelerated by the presence of certain alcohols and the combination of the sodium hydroxide and alcohol as a solvent allowed the action to take place at room temperature and normal pressure.

The following alcohols shown in Table 4 have been tried and have proven more or less satisfactory. The preferred material is isopropyl alcohol. It has been found that when this material is used in conjunction with sodium hydroxide, it hastens the dispersion of hog hair.

The effect of various alcohols on the alkaline hydrolysis of hog hair is expressed in percent digestion in the

following table. Five percent (w/v.) hog hair was hydrolyzed with 2 N NaOH:alcohol (75:25) at room temperature, no agitation.

^a Three-phase solution developed.

^b Two-phase solution developed.

Hog hair suspended in a 2 N sodium hydroxide isopropyl alcohol (3:1 ratio) for 15 to 20 minutes causes the fibers to swell and renders them capable of being disintegrated by agitation, leaving a residue of only 10 to 25% of the original material. The rate of hydrolysis of a solution prepared by mixing 25 parts of isopropyl alcohol to 75 parts of 2 N sodium hydroxide, is shown in FIG. 1 as curve 1, while curve 2 is the rate of hydrolysis of hog hair in 2 N sodium hydroxide without the isopropyl alcohol. It can be readily seen from these curves that isopropyl alcohol increases the rate of hydrolysis. The availability of the protein material as a feed supplement may be estimated by digestion of the hydrolyzed product with trypsin or pepsin.

In order to determine the minimum time required for the solvent 2 N sodium hydroxide, isopropyl alcohol (3:1 ratio) to alter the keratin fibers sufficiently to render them pepsin digestible, hog hair was treated for various time periods after which the solutions were acidified and centrifuged, the residue was suspended in an acid solution pH 2.0 and crystallized pepsin was added to the suspension to give an E-S (enzyme-substrate) ratio of 1:50.

The hydrolysis was carried out at 37° C. for 3 hours. The residue remaining after the hydrolysis was dried and weighed. The results are summarized in Table 6, under the conditions of the experiment and reaction time of 20 to 30 minutes, the hog hair fibers were sufficiently altered to render them pepsin digestible. It is therefore apparent that the comparatively short period of 20 to 30 minutes within the critical pH of 12.0 to 14, using a 2 N sodium hydroxide isopropyl alcohol (3:1 ratio) will render hog hair almost completely digestible by pepsin.

Table 6

Solvent Reaction Time, Min.	Wt. of Dry Residue ^a after Pepsin Hydrolysis, g.	Digested by Pepsin, Percent
15.....	1.5	67
30.....	0.5	90

^a Experiment started with 5 g. of hog hair in each group.

It has been further found that an E-S ratio of 1:500 is as effective as 1:50 and fibers are digested to the same extent, that is approximately 90%. It has also been found that an increase in the initial concentration of the fibers in the base alcohol solution does not hinder the penetration and effectiveness of the pepsin. Suspension of hog hair fibers of 5%, 15% and 20% were all digested to the same extent in the same time period.

Keratin fibers modified with the base alcohol solvent, precipitated with acid and subsequently dried at 37° C. could be stored without any appreciable adverse effect upon pepsin susceptibility.

In order to determine the optimum pH for the recovery of the maximum amount of starting material after modification with a base alcohol solvent, a series of samples were prepared and altered with a base alcohol solvent and to this suspension various quantities of hydrochloric acid were added. The pH of the solution and the amount of the precipitate obtained under the varying conditions were recorded. These results are summarized in Table 7. It is apparent from this study that an acidic environment is necessary to precipitate the heterogeneous mixtures of peptides required for maximum recovery.

Alkaline solutions have a tendency to destroy cystine/cysteine with the formation of hydrogen sulfide. Insofar as there is very little methionine present in the keratin molecule of hog hair, it has been assumed that the formation of hydrogen sulfide results primarily from the destruction of cystine/cysteine. A cadmium chloride-iodometric method for the determination of hydrogen sulfide was employed in this study. It was established that 3 hours of contact with the alcohol-base solvent will result in 0.47% destruction of cystine/cysteine by this technique. This value increased to 1.75% destruction when the 5-g. hog hair sample was treated in the solvent for 3/4 hour and boiled for 1 minute in an acidic solution to remove the hydrogen sulfide formed. In either

case, the extent of destruction appears to be negligible. A chromatographic analysis of the amino acid present in hydrolyzed hog hair is set forth in FIGURE 2.

Five percent suspension of hog hair was treated for 30 minutes with a 2 N NaOH-isopropyl alcohol (75:25) at room temperature. The reaction was stopped and the modified hog hair recovered by adjusting solution pH to 6.0 with concentrated HCl. The amino acid analysis was conducted on the recovered modified hog hair by hydrolyzing with HCl and resolving the resulting amino acid mixture with a descending chromatographic technique using a system consisting of Whatman No. 1 filter paper and solvent mixture consisting of sec. butanol, formic acid and water (75:15:10). The amino acids were located and identified on the filter paper strip with the use of a ninhydrin spray and standard amino acids. The density of the dye at each spot relates directly to the amount of amino acid present. The filter paper strip with the dyed resolved amino acid spots is subsequently evaluated with an Analytrol densitometer. The densitometer describes a curve from the filter paper strip which relates the density of the amino acid spot to the area under the curve. The curve presented is therefore a qualitative and a semiquantitative amino acid analysis of the modified hog hair.

FIGURE 3 is a chromatographic determination of the composition of hydrolyzed hog hair after various lengths of times of hydrolyses showing the effect, particularly with reference to the cystine/cysteine content of the exposure of these amino acids to the alkaline hydrolyzing medium.

The reaction procedure and amino acid analysis procedure are identical to those described in FIGURE 2. The stability of cystine/cysteine which is of particular importance to the nutritional value of the finished product and which is readily destroyed in a basic solution, is evaluated in these curves. The curves illustrate the importance of exactly defining the processing conditions. Treating a 5 percent hog hair suspension in a 2 N NaOH-isopropyl alcohol solvent (75:25) at room temperature without agitation causes no destruction of cystine/cysteine for 30 minutes. After 40 minutes the cystine/cysteine spot disappears which is indicative of the destruction of this amino acid. These curves also illustrate that there is no destruction of the base sensitive amino acids, arginine, aspartic acid, threonine and serine after 50 minutes of treatment.

Under these conditions, the reaction time must not exceed 30 minutes.

Prior to this time it is visually evident that the individual hair fibers are swollen and very soft and easily disintegrated. Experiments have therefore demonstrated that using the above mentioned conditions the reaction time could be reduced to 15-20 minutes if the hair suspension is agitated. Agitation can be accomplished with a blender or a mechanically driven stirring rod.

The tests on animals using a hog hair feed supplement prepared as outlined above has demonstrated that the protein obtained was an acceptable feed supplement. The substitution of modified hog hair protein for 20% of the protein in the standard soyabean meal diet showed that this feed was a satisfactory feed for the growth of animals. Feed tests on growing animals demonstrates that extended digestion periods from 3/4 hour, to 7 hours, in the modification of hog hair reaction time, in isopropyl alcohol 2 N sodium hydroxide did not destroy all the biological value of hog hair.

The growth rate of rats on a diet containing 20% of protein as modified hog hair is set forth in FIGURE 4.

Eleven 21-day-old Sprague-Dawley rats were used for each diet. The diets were prepared from a standard protein-free diet (Nutritional Biochemical Corp.) to which soyabean meal protein (SBMP) was added. The control diet contained SBMP at a level of 10 percent and the test diet contained 8 percent SBMP and 2 percent treated hog hair. The prepared hog hair had a composition in accord-

ance with the description in FIGURE 3. The final analysis of the data is presented in the accompanying table. It is to be noted that there is no statistical difference between the two groups.

Table 8
RESULTS OF SUMMARY EXPERIMENT ON RAT GROWTH RATES

Group	Number of Rats	Av. Final Wt., g.	Standard Deviation	Wt. Range, g.	t Value	Probability
10% SBMP	11	247.3	19.4	266.7-227.9	0.46	0.5
8% SBMP+2% HHP	11	224.4	20.2	244.6-204.2		

The feeding test was repeated with White Leghorn 1-day-old cockerels. The basic diet was obtained from the Nutritional Biochemical Corporation. As in the previous test the control diet contained 10 percent SMP and the test diet 8.0 percent SMP and 2.0 percent modified hog hair. The results of the test are summarized in the following table. Once again no statistically significant differences occur between the two groups.

Table 9
GROWTH RATES OF CHICKS FED MODIFIED HOG HAIR DIETS

Group	Number Chicks	Av. Final Wt., g.	Standard Deviation	Wt. Range, g.	t Value	Probability
10% SBMP	20	56.4	14.5	70.9-41.9	0.22	0.5
8% SBMP+2% HHP	20	59.1	19.3	78.4-39.8		

OTHER TISSUES

Intestines and skin

The 2 N sodium hydroxide isopropyl alcohol (75:25) was successfully used for the digestion of hog intestines and skin. The procedure has the unique advantage of solubilizing the protein and freeing the fat. The fat forms an immiscible layer which floats and can readily be removed. If the fat layer is not washed free of sodium hydroxide and heated to 60 C., the fat will be hydrolyzed and free fatty acids formed. The method is an effective method for rendering tissues and could replace present procedures.

Specifically, the following tests were performed. Initial efforts were devoted to determining whether these tissues can be processed with this solvent and whether fat, protein, and solvent can be recovered in separate fractions. The tissues were ground and the moisture and fat content were determined. The skin containing 31% solids and the intestines 60% solids. On a dry weight basis each tissue contained approximately 64% fat, of which approximately 6% was in the free fatty acid form. As in the case with hog hair, a 10% suspension of either intestines or skin was prepared in a 2 N sodium hydroxide isopropyl alcohol (3:1) solution and digested for approximately 2 hours. The protein was precipitated by the addition of acid to a pH within the range of 2:6. This protein was used in feeding tests similar to that obtained from the other examples. Addition of solid sodium hydroxide to the 2 N sodium hydroxide isopropyl alcohol solution to form a 5 N solution resulted in the formation of two liquid phases. Advantage was taken of this fact in order to separate the fat from the protein in these tissues after 2 to 4 hours of digestion.

The isopropyl alcohol layer was separated and dried. The isopropyl alcohol was readily removed by evaporation and could be subsequently condensed and recovered. Depending upon the time required for evaporation, it was determined that the fat could be recovered as fat or saponified to the free fatty acid. Saponification results from the small amount of sodium hydroxide solution, which is miscible with the isopropyl alcohol under these conditions. In either case, the fat can be entirely removed from the tissue and recovered as either the fat or the free fatty acids.

The lower layer in the 5 N sodium hydroxide isopropyl alcohol system contained the protein. Numerous attempts were made to recover the protein material and the sodium hydroxide solvent. The only method which suc-

cessfully removed the protein was acidification of the solution with hydrochloric acid. The proteins were removed 15 100%; however, the solvent was not recoverable. Methods which were tried without success were boiling, cold temperature, coagulation, sodium alginate precipitation, and ozone precipitation.

The loss of the sodium hydroxide solution can be partially offset by the fact than 20 and 40% suspensions of

tissue can be successfully processed in 2 hours. Furthermore, the most recent studies indicate that a 1 N is sufficient to hydrolyze the protein.

Ammonium hydroxide was tried in place of sodium hydroxide. However, at all concentrations tried (0.5 to 15 N), no effect was observed. These results are similar to those previously obtained with hog hair.

Experiments demonstrate that in a 2 N or 1 N sodium hydroxide isopropyl alcohol (3:1) system, the fat floats to the surface after 1 hour of mixing. In the case of the intestine the fat forms globules the size of sodium hydroxide pellets, whereas the skin forms a fat layer. In either case the fat can readily be removed by skimming the surface, and the resulting product is unsaponified fat. 45 This method is the preferred procedure.

Hog liver and kidney tissue

Experiments have shown that homogenized hog liver and kidney tissue is readily hydrolyzed by this procedure. Specifically a 10 percent suspension of either of these tissues are reacted with a 2 N NaOH isopropyl alcohol (75:25) solvent for a half-hour. Almost (90 percent) complete solubilization occurs in this time period. Upon addition of either HCl or H₂SO₄ and adjustment of the solution to pH 6.0 a whitish flocculent precipitate is formed which is peptide in nature. The protein recovered is useful as a feed supplement just as in the other examples.

Critical factors

(1) Solvent: 2 N sodium hydroxide and isopropyl alcohol (75:25). Note: Mix prior to use and allow to cool to room temperature. Other alcohol can be used, however, isopropyl was found to be most effective.

(2) Concentration and time of agitation: The suspension of hog hair in the solvent can vary from 5 to 20 percent depending upon the extent of agitation. Without agitation a 5 percent suspension is recommended, and a reaction time of one-half hour. A 5 percent solution with agitation can be digested in 20 minutes. Twenty percent suspension can readily be digested in a blender in the prescribed time period.

3. Temperature: Room temperature (24° C.) is preferred. High temperature will digest the hair faster; however, considerable amino acid damage will occur. Tem-

perature in the range of 15° C. can be used successfully if the reaction time is prolonged.

(4) pH: Sodium hydroxide solution ranging from a pH of 12, that is 0.01 N to a pH of 14, that is 1 N to 5 N, were found to function satisfactorily, although a 2 N solution is preferred.

Nature of precipitates

Stopping the reaction and lowering the pH of the solution to pH 6.0 with either HCl or H₂SO₄ (concentrated or 1:1 dilution) produces a precipitate. The amount recovered is approximately 75 percent of the original material. Complete recovery can be achieved if the solution pH is further lowered to pH 2.0.

The precipitate which is obtained at pH 6.0 is characterized by a highly charged polymeric material, grey in color with a great tendency to coalesce. The precipitated mass is further characterized by a very rubbery, spongy consistency. This mass can be washed and squeezed and it still retains its spongy character.

The protein which is recovered between pH 6.0 and 2.0 is white and flocculent.

The nature of the precipitate can be changed from a spongy form to a flocculent form if the reaction mixture is diluted one fold with water prior to the addition of the acid.

Studies have also been performed to demonstrate that FeCl₃ can react with the modified hair fibers prior to addition of the acid. Addition of one volume of 0.02 N FeCl₃ to the reaction mixture prior to the addition of the acid had several important effects. Namely less acid was required to neutralize the reaction mixture to pH 6.0 and secondly it is presumed that the ferric and chloride ions interacted with the ionic groups on the protein surface. The net result of this interaction is a decrease interaction between adjacent protein molecule changing the nature of the precipitate from a spongy mass to a flocculent precipitate.

The spongy mass due to its strong intermolecular protein adjunction produces material which can be used for protein films and fibers.

This application is a continuation-in-part of applicants' prior pending application Serial No. 749,049, filed July 17, 1958; and Serial No. 176,067, filed February 27, 1962, both applications now being abandoned.

What is claimed is:

1. A process for the preparation of a proteinaceous product which can be hydrolyzed by pepsin, which consists in contacting a material containing scleroprotein with a liquid consisting of a lower aliphatic alcohol and an aqueous alkali hydroxide, said liquid having a pH of 12 to 14, at ambient temperature and normal pressure, adding a mineral acid to lower the pH to 2 to 6 and separating the protein.

2. A process for the preparation of a proteinaceous product which can be hydrolyzed by pepsin, which consists in contacting a material containing keratin with a liquid consisting of one part of isopropyl alcohol and two

parts of an aqueous sodium hydroxide, said liquid having a pH of 12 to 14, at ambient temperature and normal pressure, adding a mineral acid thereto to lower the pH to 2 to 6 and separating the protein.

5. A process for the preparation of a proteinaceous product high in cystine/cysteine ratio protein which can be hydrolyzed by pepsin, which consists in contacting a material containing scleroproteins with a liquid consisting of a lower aliphatic alcohol and an aqueous alkali hydroxide, said liquid having a pH of 12 to 14, at ambient temperature and normal pressure for a length of time not exceeding 30 minutes, adding a mineral acid thereto to lower the pH to 2 to 6 and separating the protein.

10. A process for the preparation of a proteinaceous product having a high cystine/cysteine ratio which is hydrolyzable by pepsin, which consists in contacting a material containing keratin with a liquid consisting of isopropyl alcohol and an aqueous sodium hydroxide solution, said liquid having a pH of 12 to 14, at ambient temperature and pressure, with agitation, for a period of time not exceeding 30 minutes, adding a mineral acid thereto to lower the pH to 2 to 6, and separating the protein.

15. A protein having a high cystine/cysteine ratio which is characterized by being hydrolyzable by pepsin, said protein being prepared by contacting a keratin containing material with an aqueous solution consisting of an aqueous alkali hydroxide solution and a lower aliphatic alcohol at a pH of 12 to 14, at ambient temperature and normal pressure for a period of time not exceeding 30 minutes, sufficient to dissolve a keratin containing material, precipitating the protein by reducing the pH to 2 to 6 and separating the protein.
